DESIGN FOR A HOUSECOAT OR SIMILAR ARTICLE

Leo A. Marcus, New York, N. Y.

Application May 21, 1937, Serial No. 69,459

Term of patent 3½ years

To all whom it may concern:

Be it known that I, Leo A. Marcus, a citizen of the United States of America, residing in Manhattan, county of New York, and State of New York, have invented a new, original, and ornamental Design for a Housecoat or Similar Article, of which the following is a specification, reference being had to the accompanying drawing, forming part thereof, wherein,

I claim:

The ornamental design for a housecoat or similar article substantially as shown, and described.

LEO A. MARCUS.
